UNITED STATES PATENT OFFICE.

GEORGE S. BOUTWELL, OF NEW BEDFORD, MASSACHUSETTS, ASSIGNOR TO
THE PAIRPOINT MANUFACTURING COMPANY, OF SAME PLACE.

DESIGN FOR A HANDLE FOR KNIVES, &c.

SPECIFICATION forming part of Design No. 22,564, dated June 27, 1893.

Application filed January 18, 1893. Serial No. 458,840. Term of patent 14 years.

To all whom it may concern:

Be it known that I, GEORGE S. BOUTWELL, a citizen of the United States, residing in New Bedford, in the county of Bristol and State of Massachusetts, have invented and produced a new and original Design for Knife and other Handles, of which the following is a specification, reference being had to the accompanying drawing, which illustrates my design.

10 The leading feature of my design consists in the handle having circumferential grooves, one near the butt end of the handle; and two, separated by a band, near the inner end of the handle.

15 a' is the circumferential groove near the butt end of the handle; a^2 , a^3 are circumferential grooves near the inner end of the handle. These grooves, a^2 , a^3 are separated by

a band a^4 . The configuration of the handle is its distinguishing characteristic. In practice, the main part of the handle and the circumferential grooves and the band which separates the grooves near the inner end of the handle are finished in such wise as contrast; *i.e.* as shown in the drawing, the parts, 20 b , b' , and b^2 of the handle are "frost" finished, and the grooves and band are finished bright.

What I claim is—

The design for a knife or other handle here- 30 in set forth.

GEORGE S. BOUTWELL.
